P. L. HAISLIP.
ELECTRIC LIGHTING FIXTURE.
APPLICATION FILED OCT. 11, 1921.

1,424,095.

Patented July 25, 1922.

Inventor

Pliny L. Haistip,

By William D. Deane
his Attorney

UNITED STATES PATENT OFFICE.

PLINY L. HAISLIP, OF WASHINGTON, DISTRICT OF COLUMBIA.

ELECTRIC-LIGHTING FIXTURE.

1,424,095.

Specification of Letters Patent. Patented July 25, 1922.

Application filed October 11, 1921. Serial No. 507,059.

To all whom it may concern:

Be it known that I, PLINY L. HAISLIP, a citizen of the United States, residing at Washington, District of Columbia, have invented certain new and useful Improvements in Electric-Lighting Fixtures, of which the following is a specification, reference being had therein to the accompanying drawing.

This invention relates to improvements in fittings to be used in wiring a building or apartment for electricity, and more particularly to fittings employed in the original wiring or in wiring a building or apartment that has been previously illuminated by gas.

The primary object of the invention is to furnish an improved fitting designed to prevent a short circuit from causing a fire within the building or dwelling. At the present time fittings are employed, which when the insulation wears or burns from the conducting wires, permits the current to travel along the fittings and cause sparks which are the frequent means of starting a conflagration. It is the purpose of this invention to eliminate the defects in the known fittings.

Another object of the invention is to provide an improved insulating sleeve designed to support the ordinary cap which is placed at the upper end of an electric fixture adjacent the ceiling.

With the foregoing objects outlined and with other objects in view which will appear as the description proceeds the invention consists in the novel features hereinafter described in detail, illustrated in the accompanying drawing, and more particularly pointed out in the appended claims.

Referring to the drawing:

Figure 1 is a vertical sectional view of one of my improved fittings showing the same applied to a gas pipe and supporting the cap of an electric fixture.

Fig. 2 is a horizontal sectional view taken on line 2—2 of Fig. 1.

Fig. 3 is a horizontal sectional view taken on line 3—3 of Fig. 1.

Fig. 4 is a detail view partly in section of one of the sleeves which I have devised for use in connection with the original wiring of a building or apartment.

Figure 5 is a bottom plan view of an insulating plug used in connection with the construction shown in Figures 1, 2 and 3.

In the embodiment of the invention illus-

trated in Figures 1 to 3 inclusive, 1 designates a ceiling through which projects a gas pipe 2. When a building formerly illuminated by gas is to be wired for electricity, the gas fixture (not shown) is removed from the gas pipe 2, and a ceiling fitting 3 is placed in the plaster of the ceiling with its nipple 4 surrounding the pipe 2. Then my improved insulating sleeve 5 is placed over the projecting end of the gas pipe 2 and an insulating plug or cap 6 is screwed onto the open end of the gas pipe. The sleeve and cap are made of any suitable insulating material but preferably of some strong material capable of supporting weight. As shown, the sleeve 5 is provided with exterior threads 7 which are adapted to engage internal threads provided on a ring 8 having projecting arms 9.

The ring 8 may be adjusted vertically on the sleeve 5 by turning said ring to cause its threads to travel up or down on the threads of the sleeve, and the arms 9 are provided with threaded apertures 10 for a purpose hereinafter described.

When the sleeve 5, ring 8 and cap 6 have been placed on the gas pipe 2, the cap 11 of the electric fixture may be placed in position and locked by means of screws 12 which pass through apertures in the cap 11 and the threaded openings 10 in the arms 9 and engage the sleeve 5. These screws 12 thus serve the dual function of holding the cap 11 in position and locking the ring 8 to the sleeve 5, so that said ring will not revolve on said sleeve.

The conducting wires 13 enter the fitting 3 through an aperture 14 and pass downwardly through the cap 11 between the arms 9, and the wires pass out through a nipple 15 arranged at the lower end of the cap 11.

The plug 6, as shown in Fig. 5, is preferably provided with notches 6^a in its lower edge adapted to permit the passage of the wires 13 past the plug in a situation where the inner surface of the cap 11 abuts or nearly abuts the plug 6.

From the foregoing it is believed that the construction, operation and advantages of the described form of the invention will be readily understood by those skilled in the art, and for this reason further explanation in connection with the described form is believed unnecessary.

The construction shown in Figure 4 is

similar to that described with the exception that the fitting or box 3^a is placed in an apartment or building that has not been illuminated by gas, and for the purposes of 5 this invention the nipple 4^a is externally threaded to receive internal threads 7^a provided at the upper end portion of a sleeve 5^a which is formed of insulating material. The sleeve 5^a is also provided with external 10 threads 7^b adapted to be engaged by a ring 8^a similar to the ring 8, and this ring 8^a supports the cap 11^a in a manner similar to that described in Figures 1 to 3. No sealing plug such as 6 is necessary with this construction. 15

In both embodiments of the invention it will be apparent to those skilled in the art that the provision of the threads on the sleeves 5, 5^a, permits the rings 8, 8^a, to be adjusted vertically to accommodate caps 11, 11^a, of various sizes and designs. It will also be obvious that the provision of the insulating sleeves will prevent a short circuit under certain circumstances from causing fires 25 within buildings where the improved fittings are installed.

What I claim and desire to secure by Letters-Patent is:

1. An electric light fitting including supporting means, a sleeve of insulating material carried by the supporting means and having external threads, a ring adjustably mounted on said sleeve and having internal threads engaging the threads of the sleeve, 30 a fixture cap carried by said ring, and means accessible from the exterior of said cap for securing the cap to the ring.

2. An electric fitting including support-

ing means, a sleeve of insulating material carried by the supporting means and having 40 external threads, a ring adjustably mounted on said sleeve and having internal threads engaging the threads of the sleeve, arms projecting from said ring and having threaded apertures, a fixture cap, and screws 45 passing through said cap and engaging the threads of said apertures, said screws having their heads arranged exteriorly of the cap.

3. An electric fitting as claimed in claim 50 2, in which said ring is provided with threaded apertures registering with the apertures of the arms, said screws also passing through the apertures of the ring and engaging said sleeve.

4. In an electric lighting fitting, a gas pipe having a threaded end, a wall box having a nipple surrounding said pipe, an insulating cap secured to the threaded end of said gas pipe, an insulating threaded sleeve 60 arranged on said pipe between the cap and said nipple, a ring having internal threads engaging the threads of said sleeve, and a fixture cap supported by said ring.

5. In an electric lighting fitting of the 65 kind defined by claim 4, arms projecting from said ring and having threaded apertures, and screws passing through said cap and engaging said apertures.

In testimony whereof I hereunto affix my 70 signature in the presence of two witnesses.

PLINY L. HAISLIP.
